(57) **CLAIM**

The ornamental design for an electrical contact for use in a plating apparatus, as shown and described.

DESCRIPTION

FIG. 1 is a front view of an electrical contact for use in a plating apparatus showing our new design;

FIG. 2 is a right side elevation view thereof; the left side being a mirror image thereto,

FIG. 3 is a rear elevation view thereof;

FIG. 4 is a top plan view thereof;

FIG. 5 is a bottom plan view thereof;

FIG. 6 is a rear perspective view thereof; and,

FIG. 7 is a perspective view thereof, observed from below.
